THREE-DIMENSIONAL DECORATIVE GREETING CARD

Seymour Robins, New York, N. Y.

Application July 22, 1950, Serial No. 11,327

Term of patent 14 years

(Cl. D29—1)

To all whom it may concern:

Be it known that I, Seymour Robins, a citizen of the United States, residing at New York, in the county of New York, and State of New York, have invented a new, original, and ornamental Design for a Three-Dimensional Decorative Greeting Card, of which the following is a specification, reference being had to the accompanying drawings, forming a part thereof.

The single figure of the drawing is a perspective view of a three-dimensional decorative greeting card, showing my new design.

I claim:

The ornamental design for a three-dimensional decorative greeting card, substantially as shown.
SEYMOUR ROBINS.
